AIRCRAFT HEATER WITH WICK BURNER

John I. Trimble and William M. Myler, Jr., Co-
lumbus, Ohio, assignors, by mesne assignments,
to Surface Combustion Corporation, Toledo,
Ohio, a corporation of Ohio

Original application March 2, 1943, Serial No.
477,746. Divided and this application March
21, 1946, Serial No. 655,933

3 Claims. (Cl. 158—28)

1

The present invention relates to an air heater for use in aircraft and has for its object to embody in the heater a combustion unit which shall permit the volume rate or velocity of combustion supporting air supplied to the unit to be varied over a relatively wide range without danger of blow-out of the combustion flame. A combustion unit of this kind has special utility in a heater for use in aircraft for reasons presently appearing.

For a consideration of what we believe to be novel and our invention, attention is directed to the following specification and the claims appended thereto.

This application is a division of our abandoned application Serial No. 477,746, filed March 2, 1943.

In the drawing, the single figure is an axial section of the improved heater.

The improved heater comprises a cylindrical combustion chamber 1 formed by a cylindrical shell or barrel 8 which at its front end is closed by a head member or wall 2 and which at its opposite or exhaust end is closed by an ordinary flat wall 3. The barrel is positioned in an elongate cylindrical casing 25 which defines a passage for the air to be heated. The casing 25 at its front end is closed by an ordinary end wall 26 from which there extends outwardly a relatively short air inlet pipe 27 adapted for connection with a main air supply line or duct 30 already installed in the airplane and which leads from an air scoop or the like so that the air pressure in the air line will ordinarily vary with the speed of the airplane. The heated air passes from the casing at its far end through an outlet 31 adapted for connection with a hot air distributing duct 32 already installed in the airplane. A damper 33 may be provided in said outlet 31 to control the effective discharge area of the latter.

The fuel and the air for supporting combustion thereof are separately introduced into the combustion chamber 1. The fuel, such as engine gasoline, is supplied to the front end of the combustion chamber by a non-combustible wick or porous body 6 in the form of a disk positioned within the barrel 8 next adjacent the front end closure 2. The wick is kept wet with liquid fuel by a small feed pipe 15 embedded therein, the pipe leading from a metering nozzle 10 carried by a fitting 16 which extends outwardly from the wall of the barrel 8 opposite the rim of the wick. The fuel supply line leading to the metering nozzle is indicated at 1. The fuel in the wick is initially heated to ignition temperature by a heating coil 11 which extends through and beyond

5 a central aperture in the wick, the coil being mounted on a plug 13 secured in a fitting 14, which extends outwardly from the end closure 2 of the barrel 8. A current carrying conductor for the heating coil is indicated at 12.

10 The air for supporting combustion of the fuel enters the combustion chamber 1 through an air inlet 4 in the side of the barrel 8 at a point a short distance in advance of the wick. A stream of air is conducted to the air inlet by means comprising a conduit 5 which is tangent to said shell or barrel 8 at said inlet so that the air on entering the combustion chamber will whirl therein and thereby impart a corresponding whirl to the advancing fuel and thus produce a whirling flame. By reason of the fact that the flame is caused to whirl by the incoming air, the volume rate or velocity of air thus supplied to the combustion chamber may be varied over a relatively wide range without 15 danger of blow-out of the flame primarily because the increased linear velocity of the incoming air affects the whirling flame substantially only to the extent of increasing its rotational velocity without substantially decreasing the tendency of 20 the flame due to its whirling to ignite and reignite the unburned fuel.

25 It will be understood that at high altitudes a greater volume of atmospheric air is required to burn a given weight of fuel than at low altitudes 30 because of the decreased density of the air at high altitudes. However, if we assume that the present heater will ordinarily be installed in an airplane which will not normally operate at such high altitudes as to make changes in density of 35 the atmospheric air an important factor in the operation of the heater, there remains the fact that it may be desirable to avoid the expense of an air pressure regulator in the air supply line leading to the air inlet 4 even though the air pressure 40 may vary with the speed of airplane due to air being scooped from the atmosphere as is usually the case.

45 In the present heater, the combustion-supporting air from the main air supply line 30 is conducted to the tangential air conduit 5 through a passage which may include an air scoop 34 in the air receiving pipe 27 and a conduit 35 which leads from the scoop 34 to the conduit 5. A relief valve 36 in an extended portion of the intermediate conduit 35 vents air from the latter when the air pressure in the latter exceeds a predetermined 50 maximum as determined by the setting of a spring 37.

55 Near its rear end closure 3, the barrel 8 has a side outlet 17 for exhaust products of combustion,

the outlet being in the form of a short pipe 22 which connects with an exhaust pipe 23 adapted for connection with an exhaust flue 24 already installed in the airplane. The air vented by the relief valve 36 may also flow to the exhaust pipe 23 through an intermediate length of conduit 40.

To reduce channeling of the hot combustion gases towards the exhaust port 17, there may be provided in the barrel 8 in advance of the waste gas outlet 17 a disk-type baffle 20 spaced from the walls of the barrel as indicated at 21 to provide a ring-type exhaust passage for said gases.

It may be stated that the heater is a relatively small affair having a heat output of about 15,000 B. t. u. per hour and that the inside diameter of the barrel 8 will ordinarily not be in excess of four inches.

What is claimed as new is:

1. A heater comprising a heating unit for heating a medium adapted to flow in heat exchange relation therewith, said unit comprising a cylindrical shell defining an elongated cylindrical combustion zone, an end wall closing the front end of said shell, a porous body disposed across said zone in front of said end wall for feeding vaporized liquid fuel to said zone, means for feeding liquid fuel to said body, means for heating said body to vaporize the liquid fuel, means for igniting the vaporized fuel, said cylindrical shell having an aperture in its side for the entry of combustion supporting air into said zone near the

fuel entering end thereof, and means for conducting said air to said aperture comprising a conduit which is tangent to the cylindrical shell at said aperture so that the air enters said zone tangentially for initial whirling therein, whereby the flame of combustion of said fuel will be whirled in said zone.

2. A heater as set forth in claim 1, wherein said porous body has an aperture through which the 10 means for heating the body extends.

3. In a heater as set forth in claim 1, the combination which includes a relief valve adapted to vent air from the said air conducting means when the air pressure therein exceeds a predetermined 15 maximum.
